UNITED STATES PATENT OFFICE.

WINTHROP K. HOWE, OF ROCHESTER, NEW YORK, ASSIGNOR TO GENERAL RAILWAY SIGNAL COMPANY, OF ROCHESTER, NEW YORK, A CORPORATION OF NEW YORK.

AUTOMATIC TRAIN-CONTROL SYSTEM.

Application filed November 12, 1919. Serial No. 337,527.

To all whom it may concern:

Be it known that I, WINTHROP K. HOWE, a citizen of the United States, and a resident of the city of Rochester, in the county of 5 Monroe and State of New York, have invented a new and useful Automatic Train-Control System, of which the following is a specification.

This invention relates to automatic train 10 control systems for railways.

In accordance with this invention, a controlling impulse or influence is transmitted from the track to the train at each caution signal or corresponding control point, and 15 unless the engineer at the same time takes some appropriate action in recognition or acknowledgment of the existence of danger ahead, suitable apparatus is automatically set into operation which tends to give a service

20 application of the brakes. This apparatus is preferably of such a character that the engineer may prevent or hold off the service application of the brakes, if he desires, but at the same time provision is made 25 so that if the engineer permits this apparatus to act, he will be subjected to considerable annoyance, publicity, or the like. The penalty my system imposes upon the engineer for his failure to perform his duties

30 properly, is designed to impress the engineer with his carelessness and negligence at the time, rather than by subsequent punishment or discipline; and since the engineer knows he alone is responsible for the penalty, it is 35 expected that he will be induced to be more careful, rather than attempt to circumvent the train control apparatus in some way.

The means I preferably employ to enable the engineer to pass a caution signal without

40 getting into a difficult position, is some form of a simple acknowledging or holdoff device, which on account of the ease with which it can be manipulated, tends to encourage the engineer to watch for the signals.

45 The engineer, however, might maliciously or carelessly hold or fasten this hold-off device in the hold-off position, and to obviate this possibility, my invention includes a checking or protective appliance

50 which prevents the engineer keeping the hold-off device in the operated position permanently because in so doing, he will be subjected to the same penalty that the hold-off device is intended to prevent.

55 Under ordinary circumstances, the engi-

neer may be relied upon to slow down his train, if he is fully aware of danger ahead, but in order to safeguard the train in case the engineer for any reason fails to make a timely reduction in speed, I also provide 60 suitable means for stopping the train automatically as an emergency measure, if the engineer fails to reduce the speed of his train at the proper time and to the extent required for safety. In this way the ultimate safety of the train is made doubly certain, since not only must the engineer, assisted by the train control apparatus, fail to perform his duties, but also the train control mechanism must fail, before accident 70 can occur.

My invention also contemplates various modifications and adaptations of the principles and functions above described. For example, the apparatus may be constructed 75 so that, if the engineer fails to make timely operation of his hold-off device at a caution signal, he is obliged to call for the assistance of the fireman or some one else to relieve him from the annoyance and difficulties resulting from such neglect. Also, the speed regulating features of my system may be employed separately without the apparatus providing for automatic control at a caution signal, the indication of the signal itself 80 being relied upon to inform the engineer of the necessity for reducing speed. Further, the speed regulating features may be employed to enforce any desired speed limits upon the approach to sharp curves, crossovers, drawbridges, and like permanent hazards which require the train to travel by them at a limited speed.

Other objects and features of my improved system of train control will appear 95 hereinafter during the description of the specific embodiments of my invention.

In describing the invention in detail, reference will be made to the accompanying drawings, in which Figure 1 shows in a 100 simplified and diagrammatic manner a portion of a railroad track equipped in accordance with my invention, together with some curves illustrating the contemplated performance of trains;

Fig. 2 illustrates the car equipment, together with the trackway impulse device, the parts and circuits in this view being shown more with the view of making the functions and mode of operation easy to 110

understand than with the view of showing the precise construction and arrangement of parts preferably employed in practice.

Fig. 3 is a detail sectional view of the 6 valve forming part of the hold-off device;

Fig. 4 illustrates a modified construction of the engineer's hold-off device;

Fig. 5 illustrates a modified construction of the car equipment in which the cooperation 10 of the fireman, or some person other than the engineer, is required to get the engineer out of the difficult position in which he is placed when he fails to make timely operation of his hold-off device;

Fig. 6 illustrates a modified construction 15 of a resetting or restoring device;

Fig. 7 illustrates a modification of my system involving the speed regulating features, without the automatic control at the 20 caution signals;

Fig. 8 illustrates how the system may be arranged to enforce two or more different speed restrictions in a caution block; and

Figs. 9 and 10 illustrate how any desired 25 speed limits may be enforced upon the approach to a crossover or sharp curve, respectively.

Referring first to Fig. 1 which illustrates the trackway equipment, the track rails 1 30 of the railroad track are divided by insulated joints 2 into blocks in the usual way, two complete blocks B and C with the adjacent ends of two other blocks A and D having been shown. For the purpose of 35 illustrating the applicability of my invention to different length blocks, the block C is assumed to be longer than the block B. The trackway equipment associated with the various blocks is the same, and for convenience the various parts and circuits will be given like reference characters with distinctive exponents. Each of the blocks is 40 provided with a track battery 3 and a track relay 4, constituting the well known normally closed track circuit. My system of 45 automatic train control is preferably used in connection with the usual fixed signals of the well known automatic block signal system, and such signals S are illustrated conventionally in Fig. 1 the controlling circuits for 50 such signals being omitted for the sake of simplicity.

Associated with each of the blocks is a 55 cautionary track-way element T, which is located at a distance from the end of the block sufficient to permit a train, running at its maximum speed, to be stopped in the way ordinarily employed by engineers in 60 making a service stop. In cases where the length of the block is substantially the same as this service stopping distance, the caution trackway element T is located at or adjacent to the entrance of the block, as exemplified in the case of the block B in 65 Fig. 1. In instances, however, where the

blocks are longer than the distance usually required to make a service stop, I prefer to locate the caution trackway element T at the appropriate point inside of the block and beyond the entrance thereof, as exemplified in case of the block C in Fig. 1, although this is optional.

In addition to the cautionary trackway element T, a pair of trackway elements T^a and T^b are located at the appropriate control 75 point between the ends of the block and at the appropriate distance apart, all as explained hereinafter.

Various types of means for transmitting 80 impulses from the track to the train may be employed in my improved system, but I prefer to employ impulse transmitting means of the inductive type and have illustrated one form of such inductive means. The particular type of trackway element 85 illustrated (see Figs. 1 and 2) comprises a U-shaped core or yoke of magnetic material having enlarged ends constituting pole pieces, and provided with a coil 5. This trackway element may be located crosswise 90 or lengthwise of the track, between or outside of the track rails, and in practice would be encased and protected against the weather, dragging brake beams and the like. 95 In the arrangement of trackway circuits illustrated, a circuit for the coil 5 of each of the trackway elements of each block is controlled by the front contact of a line relay 6, or 6^a, the controlling circuit for these 100 line relays being governed by the track relay of the next block in advance. This arrangement is only typical, and is susceptible of change and modification. The essential requisite for my system of train control is that the trackway elements of 105 each block shall be placed in the stopping condition when the next block in advance is occupied, and in the type of impulse transmitting means illustrated, this is accomplished by opening the circuit for the coils 5 of the several trackway elements by means 110 of line relays.

Referring now to Fig. 2, the car equipment comprises a car-carried element L adapted to be influenced by the trackway elements T, T^a and T^b when these have their coils 5 open-circuited; a hold-off device H, arranged for convenient operation by the engineer and protected so as to prevent the engineer from keeping it in the operated position; a pneumatic device F tending to move the engineer's brake valve to the service position, whenever the train passes a trackway element in the stopping controlling condition, and the engineer fails to operate his hold-off device H; and finally, a time controlled apparatus K which, in conjunction with the pair of trackway elements T^a and T^b at an intermediate point in a 120 caution block, acts automatically to cause 130

an application of the brakes independently of the engineer, if the speed of the train at said intermediate point is above a predetermined minimum. If desired, of course, instead of an emergency application of the brakes, a heavy service application may be used; but, in order to carry out the intended operation, I prefer to employ a brake application which is as powerful as it is safe and desirable for the equipment, so as to obtain maximum protection for the train and also impose a real penalty upon the engineer, all as explained hereinafter.

The car-carried element L comprises an inverted U-shaped core or yoke 7 of magnetic material, preferably laminated, which is provided with the usual pole pieces, and is carried by the locomotive or other railway vehicle so as to pass over the trackway elements T, T^a and T^b. Each leg of the yoke 7 carries a coil designated 8 and 9, respectively. The coil 8, conveniently termed the field coil, is constantly supplied with current from a battery 10, and produces a magneto-motive force tending to send flux through the yoke 7. Also included in circuit with the battery 10 and the coil 8 is a check relay X which, on account of its operating characteristics hereinafter explained, serves to detect an interruption or cross in this circuit. The secondary coil 9 is connected in circuit with a control relay R and a small battery 11. The detail features of construction of the car-carried and trackway elements form no part of my present invention, and are merely illustrative of a type of inductive impulse transmitting means which may be employed in my improved system.

Both of the relays R and X are preferably of the balanced type so as to be responsive to either an increase or decrease in the normal current for which the relay is adjusted. In the simplified construction illustrated, the armature 12 of the relay is biased by a spring 13, and is provided with an insulated striking piece 14. This striking piece 14 is positioned between two resilient contact springs 15-15¹ which normally press against two electrically connected and fixed contacts 16 designated conventionally by arrows. The spring 13 is adjusted so that, with the normal current flowing in the winding of the relay, its armature 12 is balanced. If this normal current is increased, the attraction of the armature 12 overcomes the spring 13, and the striking piece 14 moves contact spring 15 out of contact with its cooperating contact 16. On the other hand, if the normal current is decreased, the spring 13 overbalances the armature 12 and causes separation of contact spring 15¹ from its cooperating contact 16. The circuit controlled by the relays R and X is carried through the contact springs 15 and 15¹ and

the fixed contacts 16, so that this circuit is opened whenever the current normally flowing through these relays is either increased or decreased.

The engineer's hold-off device H shown in Fig. 2 comprises a casing 17 in which the several parts are enclosed for protection and also to prevent unauthorized interference, this casing being in practice provided in the usual manner with a suitable sealed or locked door or cover (not shown) which permits access to the interior by authorized persons for inspection and maintenance. Within the casing is a rotary valve V. A lever 18 is fastened to the stem of the valve V and projects out of the casing through a slot 19. This lever 18 is preferably provided with a suitable handle for facilitating its manual operation, and also a latch 18^a of suitable construction (illustrated in a simplified and conventional manner) which is adapted to cooperate with a notch in a curved ridge or sector 20 integral with the casing. This sector 20 is provided with a shoulder 21 near one end constituting a stop for the lever 18 in its operated or hold-off position. The other end of the lever 18 carries an insulated contact block 22 which is adapted to bridge a pair of stationary contacts 23 (shown conventionally as arrows) when the lever is shifted to its operated or hold-off position, as partially shown in dotted lines. Compressed air is supplied to the valve V from the main reservoir, or other source of pressure, through a pipe 24; and when the lever 18 is moved to its operated position, the valve V is shifted so as to open communication from the pipe 24 through passage 25 and recess 26 in the valve (see Fig. 3) to a pipe 27. Pipe 27 communicates through an adjustable restricted orifice 28 (illustrated conventionally) to a small reservoir 29; and this reservoir 29 is in turn connected by pipe 30 with a cylinder 31. An air-tight piston 32 in the cylinder 31 is urged by a compression spring 33 to the left hand position as shown in Fig. 2; and its piston rod 34 carries a head 35 of insulating material, which engages a contact spring 36 when said piston rod is projected, thereby separating said contact spring from its cooperating contact 37, shown conventionally as an arrow. With the lever 18 in its normal position, as shown, cylinder 31 and reservoir 29 are exhausted to atmosphere through recess 26, passage 25 and port 38 (see Fig. 3).

The apparatus for giving an automatic application of the brakes when the engineer fails to operate his hold-off lever 18, providing the engineer does not oppose such automatic application, may take various forms. In the construction illustrated in Fig. 2, I provide a pneumatic device F which is coupled to the engineer's brake valve and which acts, when set into operation, to exert

a strong pressure tending to shift the brake valve to the service position, this pressure, however, being small enough to enable the engineer to hold his brake valve against 5 movement by some exertion, and being continued for such a length of time that the difficulty in holding the brake valve against movement would become objectionable and obnoxious to the engineer. The engineer's 10 brake valve E and its usual operating handle 40 are illustrated conventionally. A sector 41 is fastened to the stem or shaft of the brake valve E in a suitable manner so that as the sector 41 is swung, the brake valve will be 15 shifted to apply the brakes. The sector 41 meshes with a rack 42, which is integral with or connected to a rod 43. The rod 43 passes through one end of an operating cylinder 44, and loosely through a piston 45 in said 20 cylinder, the end portion of said rod 43 being screw-threaded and provided with two adjustable clamping nuts 46 against which the piston strikes when moved to the right, as viewed in Fig. 2. Stops 47 fastened to the 25 cylinder 44 limit the righthand movement of the piston 45; and by adjusting the nuts 46, this limited movement of the piston 45 may be employed to shift the engineer's 30 brake valve accurately to the service position, or if desired, to an emergency position. The rod 43, since it slides loosely through the piston 45, does not prevent the engineer moving his brake valve handle 40 to any position he desires while running his train in 35 the ordinary way.

Fluid pressure from the main reservoir or the like is automatically supplied to the cylinder 44 on the lefthand side of the piston 45 (as viewed in Fig. 2) through a pipe 48, when an electropneumatic valve E. P. V. is 40 deenergized; and this pressure may escape to atmosphere gradually through a pipe 49 and an adjustable restricted orifice 50. An air whistle 51 may be attached to the pipe 49 45 so that the escaping air will sound the whistle and give publicity to the fact that the engineer has been negligent. Such a whistle, while not an-essential part of my proposed system, is desirable because it introduces an element of publicity in connection 50 with neglect of the engineer, which with some individuals is often more of a penalty than the trouble and annoyance of holding the brake handle.

Various types of electropneumatic valves 55 may be employed to supply pressure to the cylinder 44. In the particular construction illustrated, the armature 52 of the usual magnet or solenoid 53 is fastened to a stem 54 which bears against the double-ended and differential piston valve 55. The pipe 48 is in communication with a chamber 56, which normally, that is, when the magnet 53 is energized, and its stem 54 raised, is in communication 60 with the atmosphere through the valve port 57 and passage 58. Pressure from the main reservoir or other source is supplied through an adjustable restricted orifice 59 to a small reservoir 60, and from there through pipe 61 to a chamber 62 above 70 the piston valve 55. When the magnet 53 is deenergized, pressure against the upper end of the piston valve 55, aided by a spring 63 on the stem 54, forces said piston valve down, closing the port 57 and opening communication 75 from the chamber 62 to the chamber 56 through the valve port 64 and the passage 65, thereby supplying air to the operating cylinder 44 through pipe 48. It will be noted that the area of the upper end 80 of the piston valve 55 which is exposed to pressure in the chamber 62, is greater after this piston valve has moved down to its open position than when said valve is closed, and the parts are so proportioned that this increased pressure prevents reclosing of the piston valve 55 by energization of the magnet 53 until the pressure in reservoir 60 and chamber 62, has dropped to a predetermined value. The restricted orifices 50 and 59 are 85 adjusted so that the air escapes from the cylinder 44 through orifice 50 faster than it is supplied from the main reservoir through the restricted orifice 59, so that after a lapse of a certain time, depending upon the size 90 and proportioning of the parts, the pressure in the reservoir 60 and chamber 62 drops to the critical value at which the valve 55 may be closed by the magnet 53. This construction 95 provides a simple apparatus which 100 acts, upon deenergization of the magnet 53, to supply pressure to the cylinder 44 and thereby exert a force tending to shift the engineer's brake valve E, and which will also automatically maintain this pressure for a 105 predetermined time. Obviously, the timing operation may be obtained in other ways; and I desire to have it understood that the construction shown is merely illustrative of the desired operation and functions of this 110 part of my system.

The energizing circuit for the magnet 53 of the electropneumatic valve E. P. V. may be traced as follows: From ground, battery 66, conductor 67, magnet 53, conductor 68, contacts 37—36, conductors 69 and 70, and front contact 71 of a relay Q back to ground. The energizing circuit for the relay Q is controlled by the control relay R and relay X, this circuit being readily traced on the drawing. This relay Q is preferably quick-acting because the control relays R and X, in this type of inductive impulse transmitting device, open their contacts only momentarily. The front contact 71 of relay Q is shunted, when the hold-off lever 18 is in its operated position, by conductors 72, contacts 23, block 22, and conductor 73 to ground. Thus, the magnet 53 will always be deenergized when the contacts 36—37 are 125 130

opened, and will be deenergized when the relay Q drops, providing the hold-off lever 18 is not in its operated position at the time so as to close contacts 23.

- 5 The parts of my system so far described serve to check up the vigilance of the engineer at each caution signal or corresponding control point, and their operation may now be described with this feature of my 10 system in view. The inductive impulse transmitting means acts to drop the relay Q at each trackway element T in its stopping controlling condition, that is, with its coil 5 open-circuited, but does not affect said relay when the trackway element has its coil 5 in a closed circuit of low resistance, corresponding to a clear signal. The cautionary impulse, generally speaking, is produced by electro-magnetic induction as the car-carried 15 element passes over the trackway element. Normally, while the train is traveling between trackway elements, the current in the coils 8 produces a certain magneto-motive force which sends a predetermined flux 20 through the yoke 7 and the coil 9. When the coil 5 of the trackway element is open-circuited, corresponding to a caution signal, said trackway element presents in effect a dead magnetic loop for the yoke 7 of the car-carried element L on a passing train, and thus 25 changes the reluctance of the magnetic circuit including said yoke and coils, thereby causing a corresponding change in the flux through the coil 9. This change in flux induces the current in said coil 9 which varies 30 the current supplied to the control relay R, thereby causing it to open its contacts and momentarily interrupt the energizing circuit of the relay Q. The electro-pneumatic valve 35 E. P. V. is of course constructed so that it will operate and unseat the valve 55 (Fig. 2) or valve 104 (Fig. 5) during the momentary opening of the contacts of the relay Q. In the particular arrangement described, 40 the check relay X does not open its contacts at a caution signal, but is used to check the circuit through the field coil 8, although this particular arrangement is not compulsory. 45 Under clear traffic conditions, the coil 5 of the trackway element T is in a closed circuit of low resistance and opposes or chokes back the passage of flux through the trackway element, thereby preventing a change of flux in the yoke 7 of a passing car sufficient 50 to cause operation of the control relay R. Thus, the quick-acting relay Q is deenergized at each caution signal or corresponding control point, but is not operated under clear traffic conditions. 55 The engineer upon approaching the caution signal is expected to operate the holdoff lever 18 to its operated position. This closes contacts 22-23 and shunts the front contact 60 71 of the relay Q, so that the dropping of the relay Q does not affect the magnet 53.

In this way, if the engineer is alert and observes that the signal indicates caution, he is able, by a simple operation of the holdoff lever, to avoid a brake application. The operation of the holdoff device being an active 70 movement, is such as to impress upon the engineer the fact that he has passed a caution signal and entered a danger zone, thereby imposing upon him the responsibility of controlling his train safely. 75

If the engineer is careless or indifferent about watching the signals and fails to note that he is about to pass a caution signal, the operation of the relay Q, the holdoff lever being in the normal position, causes deenergization of the magnet 53 of the electro-magnetic valve E. P. V.; and this results in supplying pressure to the cylinder 44, as previously explained. This pressure acts to operate the engineer's brake valve E and 80 automatically applies the brakes, unless the engineer by holding the handle 40 prevents such operation. I prefer to make the pressure exerted upon the engineer's brake valve such that, while the engineer may prevent 85 movement, or replace his brake valve after movement, he is obliged to exert himself to do so. This pressure in the cylinder 44 will continue, as previously explained, for a certain selected time, depending upon the size 90 and proportioning of the parts, and the adjustment of the restricted orifices 50 and 59. 95

It may happen that the train is traveling at such a speed when it passes the caution signal that an immediate service application of the brakes is desirable; and in this case the engineer may not care to hold his brake handle against movement. It will be noted, however, that the engineer's brake valve, if 100 operated automatically, will be moved to the service position and forcibly held there for a short time; and since this would bleed the train pipe and require a longer time to recharge and release the brakes, it would be 105 something which the engineer would naturally wish to avoid. Therefore, even though the engineer does not oppose the automatic brake application, he will find it necessary 110 to move his brake valve handle in opposition to the force exerted against it by the air pressure in the cylinder 44, unless of course he waits until the time interval for which the restricted orifices 50 and 59 are adjusted 115 has expired, so that in any event he will be 120 penalized for his failure to operate his hold-off device at the right time. Moreover, this penalty is self-executed, so to speak, and obviates the objections to the practice of using recorders and trying to discipline the engineer if records are made against him. 125

Furthermore, if it should happen that the engineer is incapacitated, or unable for any reason to operate either his holdoff lever or his brake handle, the brakes will be applied 130

at the caution signal in time to stop the train safely. In this connection, I find it desirable to arrange the pneumatic device F so as to give a service application of the brakes, partly on account of the injurious effect of an emergency application upon the passengers and the equipment, and also because this automatic application of the brakes, when it occurs, will take place at or 10 near the caution signal, service braking distance from the end of the block. If desired, however, by an obvious modification or adjustment of parts, the apparatus may be arranged to give an emergency application of 15 the brakes so as to constitute a more severe penalty for a failure to observe the signals and operate the holdoff device.

Obviously, if the engineer were able to 20 keep his hold-off lever in the operated position, he would not be obliged to note each signal and make a positive movement. To obviate this, the contacts 36-37 are provided, together with their associated operating mechanism. Normally the valve V is in the 25 position shown in Fig. 3, exhausting the cylinder 31 and reservoir 29 to atmosphere. When the hold-off lever 18 is operated, the valve V supplies air through the restricted orifice 28 to the reservoir 29, so that the pressure gradually builds up in this reservoir. After a short interval of time, the pressure accumulates behind the piston 32 sufficiently 30 to compress the spring 33 and cause the insulated head 35 to separate the contacts 36-37, thereby deenergizing the magnet 53. Consequently, if the hold-off lever 18 is kept in its operated position longer than a certain time, the magnet 53 will be deenergized and the pneumatic device F operated. In other 40 words, if the engineer attempts to keep his hold-off lever 18 permanently in the operated position, he will get into as much trouble as if he failed to make timely operation of the hold-off lever at each caution signal.

45 The time interval of the operation of the checking device associated with the hold-off lever 18 may be varied to suit the particular working conditions, so as to give the engineer reasonable latitude in operating the 50 hold-off lever while approaching and passing a signal, and yet prevent him keeping the hold-off lever in its operated position while passing from one signal to another.

55 In this discussion, the automatic control has been referred to as occurring at a caution signal, or a control point corresponding to a caution signal (see block C); but it should be understood that by a simple and obvious modification of trackway circuits the 60 same automatic control may also be obtained at a stop signal as well as at a caution signal, or, where an overlap is employed, the automatic control can be obtained at the stop signals and not at the caution signals.

65 In addition to the automatic control above

described taking place at a caution signal, my system also provided for enforcing a speed restriction at one or more intermediate points in a caution block, thereby checking up the obedience of the engineer to the caution signal. Generally stated, this is accomplished by locating a pair of trackway elements T^a and T^b at the appropriate intermediate point in the block, and providing a time controlled apparatus K on the train 70 for applying the brakes automatically, and in spite of the engineer, unless the train takes more than a predetermined time in traveling from one trackway element of this pair to the other. 80

The time controlled apparatus K, while it may take various forms, is illustrated in Fig. 2 as a combined pneumatic and electrical device. A solenoid P is connected in circuit with the contacts of the control relays R and X so as to be energized or de-energized as these contacts are closed or opened, respectively. The core 74 of this solenoid carries an insulated contact piece 75 arranged to cooperate with elongated 90 contact strips 76 for part of the movement of said core. When the solenoid P is energized, its core 74 bears against a differential piston valve 77 and holds it in the closed position. Air pressure from the main reservoir or other source is supplied through a restricted orifice 78 to a small reservoir 79 which communicates through a pipe 80 with the seat of the valve 77. When the solenoid P is deenergized, the pressure in the 100 reservoir 79 unseats the piston valve 77 and raises it to uncover a passage 81 leading through the restricted orifice 82 to atmosphere. The area of the piston valve 77 exposed to pressure when it is unseated is 105 greater than when it is seated, so that the solenoid P, even though reenergized, is incapable of reclosing said piston valve until the pressure in the reservoir 79 has dropped to a predetermined amount. In order to 110 temporarily retard the upward movement of the piston valve 77, the chamber 83 above it is closed, with a small port 84 leading to atmosphere, said port being covered by said valve just before it reaches its uppermost extreme, whereby the final upward movement of the valve 77 and core 74 is 115 temporarily retarded until the confined air leaks out around said core. The restricted orifice 82 is adjusted so that the air escapes 120 from the reservoir 79 faster than it is supplied through the restricted orifice 78, and the parts are so proportioned that the solenoid P, which is only momentarily deenergized, will restore its core to the normal 125 position after the lapse of a predetermined interval of time, say, a second or two.

The apparatus K preferably controls an emergency application of the brakes. This emergency application is preferably given 130

by some suitable brake controlling valve which acts to vent the train pipe at the emergency rate. Various devices suitable for this purpose are well known in the art, 5 and I have illustrated such an emergency brake controlling valve G diagrammatically as comprising a magnet or solenoid 85 arranged so as to open a valve 86 and vent the train pipe 87 when deenergized. The 10 normally closed energizing circuit for the magnet 85 includes two branches in multiple, one including the front contact 88 of the relay Q, and the other the contact strips 76 and the contact disc 75.

15 The operation of the apparatus K is as follows: The parts are normally in the position shown when the train passes a trackway element as T^a, in the stopping condition, the control relay R is operated the same way 20 as previously described, and the quick acting relay Q and the solenoid P are simultaneously and momentarily deenergized. While the front contact 88 of the relay Q is open, the circuit for the brake controlling 25 magnet 85 is maintained closed by contact strip 76 and contact disc 75. At the instant the solenoid P is deenergized, the piston valve 77 is raised to uncover passage 81 and commence the gradual reduction in pressure 30 in the reservoir 79. On account of the temporary retardation of the piston valve 77 after it has moved up far enough to close port 84 the contact disc 75 maintains contact with the strips 76 temporarily, at least until the 35 relay Q is again picked up. After this temporary retardation in the movement of the piston valve, however, the core 74 reaches its uppermost position by the pressure against said valve, thereby breaking the branch of the 40 circuit for the brake controlling valve 85 which includes the contact strips 76 and the contact disc 75; and although solenoid P is reenergized at the same time as the relay Q, the core 74 remains in its upper position until, 45 the time interval for which the device is set having expired, the pressure below the piston valve 77 is reduced to a point where the attraction of the solenoid P is sufficient to restore the core to the normal position, 50 whereupon the branch circuit for the brake controlling magnet 85 is closed through the strips 76 and the disc 75. If, now a train should pass over a second trackway element, 55 as T^b, before the core 74 is restored to its normal position, an emergency application of the brakes would be automatically given, since one branch of the circuit for magnet 85 is broken at the contact disc 75, and the other branch would be broken by the deenergization 60 of the relay Q, as a result of the passage of the car-carried element L over this second trackway element. In other words, if the train consumes less than a certain time in passing from one trackway element to the next, the brakes are applied, 65 this interval of time being that for which the apparatus K is adjusted. If the train consumes more than this time, the brakes are not applied. Thus, by putting the trackway elements in pairs relatively close together, 70 as for example the trackway elements T^a and T^b, in the block B, Fig. 1, a limiting speed may be enforced at this point, depending upon the timing of the apparatus K, and the distance between this pair of 75 trackway elements. Obviously, by locating this pair of trackway elements closer together, or farther apart, while maintaining the same timing of the apparatus K on the train, various speed limits may be enforced. 80 It will be evident that the apparatus K applies the brakes or not depending upon the average speed of the train in traveling between the trackway elements T^a and T^b, rather than its instantaneous speed at the 85 trackway element T^b; but by locating the trackway elements such a short distance apart that a train would not be able to materially accelerate or decelerate in this short distance, the desired limiting speeds can be 90 determined with sufficient accuracy for practical purposes. The apparatus K does not act at the cautionary trackway element T, since there is time for this apparatus to be reset before the train reaches the next trackway element T^a. 95

The features of my system above described may be applied in practice to various working conditions in different ways. According to one typical application, the first or cautionary trackway element T of a block is located at a distance from the end of that block corresponding with the distance required to make an ordinary service stop, or bring the train to a low and comparatively 100 safe speed, such as five or ten miles per hour. In other words, sufficient distance is provided between the cautionary trackway element T and the end of the block to permit the engineer to make his usual stop in obedience to a caution signal. While the practice of engineers in stopping their trains varies, the distance ordinarily taken for a service stop is greater than that actually required to stop the train by a full and continued 105 service application. One way of making a service stop is represented diagrammatically in Fig. 1 by the curves drawn in dash lines. In this illustration, it is assumed that the train in question is traveling at its maximum 110 speed of sixty miles per hour (indicated by dot and dash line 89) when it passes the caution signal, and that a full service application of the brakes is made at once, the speed being reduced, as indicated by dash line 115 90, to some intermediate moderate speed, such as thirty or thirty-five miles per hour (indicated at 91, whereupon the brakes are partially or wholly released, and the train allowed to coast until within approximately 120 125 130

the proper distance from the end of the block, when the final reduction in speed is made by a full service application, as indicated by curve 92. Whether the service 5 stop is made according to this method, or in some other way, as for example, by a partial service application held on for the full stop, there is an intermediate point in the block (indicated by the vertical line 93 in the 10 particular example illustrated in Fig. 1) where a moderate speed, shown as 30 miles per hour, is high enough to avoid unnecessary delay in making the service stop, and low enough to permit the train to be 15 stopped by an ordinary service application before reaching the end of the block. Having determined this moderate critical speed limit, and the intermediate point where it should be imposed, the trackway elements T^a 20 and T^b will be located at this point and the proper distance apart to act in conjunction with the timing of the apparatus K and give an emergency application of the brakes if this critical speed is exceeded at this point. It 25 is recognized that some engineers have the objectional practice of running by caution signals, that is, delaying a reduction in speed and running so far into the block at high speed, in expectation of finding the next 30 signal at caution or clear, as to make it difficult or even impossible to stop. By checking up the speed of the train at an intermediate point in the block my system stops, to a large extent at least, this objectionable practice, because the engineers wish 35 to avoid emergency applications and would, therefore, make a proper and prompt reduction in speed so as to be below the critical speed at this intermediate point. The 40 disciplinary effect of the emergency application may be increased, if desired, by arranging and constructing the emergency brake controlling valve G, in a simple and obvious manner, so that, after having been operated, 45 it must be reset from the ground, or some other inaccessible place, thereby requiring the train to be brought to a stop before this valve can be closed and the train pipe recharged to permit release of the brakes. Or, 50 the re-setting device for the valve G may be time-controlled, so that the brakes cannot be released until after a short time, somewhat longer than that required to bring the train to a stop. 55 In order to afford as much automatic protection as possible, I prefer to locate the trackway elements T^a and T^b so that, as far as practicable, they would act to stop the train safely under the worst conditions. 60 For example, the braking curve for an emergency application, starting at maximum speed and running out at the end of the block, is shown by the full line 94 in Fig. 1. It will be noted that this emergency braking curve, according to the particular ex- ample illustrated, starts at the point where the trackway element T^b is located. By doing this, a safe stopping of the train is assumed under the worst conditions, because even if the engineer makes no reduction in speed and passes the pair of trackway elements T^a and T^b at the maximum running speed, the resulting automatic emergency application will stop the train before it reaches the end of the block. It is evident, 75 of course, that the braking power of trains varies, and also the manner of making service stops, so that the desirable arrangement illustrated by the curves shown in Fig. 1 cannot be always attained. In all cases, 80 however, I prefer to locate the trackway elements T^a and T^b as far back from the end of the block as possible without imposing any useless restriction upon the speed at which the train may safely travel at this 85 point and make an ordinary service stop; and although this distance, which may be satisfactorily obtained, may not be as great as emergency braking distance for maximum speed, it will serve to cut down the 90 speed at least, and in most instances, prevent the train running at high speed from colliding with another train standing just ahead of the entrance to the next block. Obviously, the exact location of this pair of 95 trackway elements T^a and T^b in a block, and the variation in their spacing so as to enforce different speed limits, will depend upon the grades, braking power of the 100 train, and other working conditions for that particular block; and I desire to have it understood that the particular location and arrangement indicated in Fig. 1 is merely 105 illustrative of features of my system and is susceptible of variation in practice. Also, 110 while I have shown only one pair of trackway elements T^a and T^b in the block, two or more pairs may be employed in the same way to enforce several intermediate speed limitations.

Since the electropneumatic valve E. P. V. would be operated at the trackway element T^a the same as at the trackway element T at the caution signal, provided the engineer did not operate his hold-off device H, it is 115 desirable to place a marker M along the track to indicate to the engineer the position of this trackway element T^a , so that he is given opportunity to operate his hold-off device. A similar marker N is also employed 120 where a trackway element, as in the case of the block C, is not located at the signal, but at some point further in the block. The trackway elements T^b would not ordinarily require markers, since they would be such 125 a short distance from the trackway elements T^a that the engineer might pass both with a single operation of his hold-off device.

Fig. 4 shows a modified construction of the engineer's hold-off device, which in gen- 130

eral is similar to that shown in Fig. 2. In this modified construction, the contacts 36—37 are opened after a short time following the movement of the hold-off lever 18 to its operated position, by a pneumatic timing device O, which is normally held inactive by the lever 18 and is released by the movement of said lever to its operated position. This time device O comprises a cylinder 95 containing a piston 96 which is urged in one direction (to the right as viewed in Fig. 4) by a spring 97. This movement of the piston 96 by the spring 97 is retarded by the air which is compressed in the right-hand end of the cylinder 95, and which can escape only gradually through a restricted orifice 98. The piston rod 99 connected to said piston 96, carries at one end an insulated striking piece 100, which is arranged to strike the contact spring 36 and separate it from its cooperating contact 37, when the piston attains its righthand position. The other end of the piston rod 99 extends through a suitable air-tight packing or stuffing box in the end of the cylinder 95 into position to be engaged by the upper end of the lever 18. A suitable ball check valve 101 is provided to allow quick return of the piston 96 to its normal position shown in Fig. 4.

The operation of this modified construction of the engineer's hold-off device will be readily apparent. When the lever 18 is moved to its operated or hold-off position, the piston 96 is free to be moved gradually to the right by the spring 97 at a rate determined by the adjustment of the restricted orifice 98; and after the lapse of a predetermined time, the striking piece 100 opens the contacts 36—37. Thus, the lever 18 may be swung to its operated position, held there a short time and then returned to the normal position, without opening contacts 36—37; but if said lever is held in its operated position longer than a certain time for which the device is adjusted, the contacts 36—37 will be opened to cause deenergization of the electropneumatic valve E. P. V. in the same way as previously described.

Fig. 5 shows a modified construction of my system, in which the application of pressure to the engineer's brake valve, resulting from a failure of the engineer to operate his hold-off device H at a caution signal, will continue until the fireman, or some person other than the engineer, releases this pressure. In this modification, the engineer's hold-off device is the same as shown in Fig. 2, and likewise the pneumatic device F for operating the engineer's brake valve, except that the cylinder 44 in the modified construction is not provided with the restricted orifice 50 as in Fig. 2. Also, the electropneumatic valve E. P. V. is modified

so that it is reset electrically, rather than automatically by a reduction in pressure. In this modified construction of the electropneumatic valve E. P. V., the stem 54 is provided with an insulated contact disc 102 which bridges fixed contacts 103—103 when said stem is in its uppermost position, as shown in Fig. 5. This stem 54 carries two opposed valves 104 and 105. The upper valve 104 controls the supply of compressed air from an upper chamber 106, which is connected by pipe 107 to the main reservoir, to the lower chamber 108, which communicates by pipe 48 with the cylinder 44. The lower valve 105 controls the connection between the chamber 108 and a passage 109 leading to atmosphere. A spring 110 on the stem 54 acts in conjunction with the main reservoir pressure on the control valve 104 to move the stem downward when the magnet 53 is deenergized. In this arrangement, the magnet 53 when energized is strong enough to reclose the valve 104 against main reservoir pressure as well as hold it closed.

The fireman's reset device U comprises a manually operable plunger 111 projecting out of a casing 112 in which the several parts of the device are enclosed in the same way as the engineer's holdout device H. This plunger is guided by said casing and a lug 113 integral with said casing. The plunger 111 has an insulated head 114 at its lower end arranged to move a contact spring 115 into contact with its cooperating contact 116 when said plunger is pushed down. A compression spring 117 between the lug 113 and a collar 118 on the plunger 111 holds the plunger yieldingly in its normal uppermost position, as shown in Fig. 5. The plunger 111, like the lever 18 of the engineer's hold-off device H, is provided with a safety appliance for preventing it being carelessly or maliciously held or fastened down. This safety appliance comprises a lever 119 suitably pivoted between its ends to the casing 112. The lever 119 is biased to swing in one direction (counterclockwise as viewed in Fig. 5) by a spring 120, and is swung in the opposite direction by the upward movement of the plunger 111, the end of said lever being engaged by the collar 118. This lever 119 carries an insulated striking piece 121 arranged to hit a contact spring 122 and separate it from its cooperating contact 123, when said lever is swung by the spring 120 to its extreme position. The movement of the lever 119 under the influence of the spring 120 is retarded by a dashpot comprising a cylinder 124, having a restricted exhaust port 125 in its bottom, and a piston 126, provided with flexible packing and connected by a rod 127 to the lever 119.

Normally, the parts of the fireman's reset device U are in the position shown in Fig. 5. 130

When the plunger 111 is pressed down by the fireman to close contacts 115—116, the lever 119 is free to be swung by the spring 120. The downward movement of the piston 126 is retarded by the slow escape of air from the cylinder 124 through the exhaust port 125, so that the lever 119 does not move far enough to open contacts 122—123 until after the lapse of a short interval of time. When the plunger 111 is released, the spring 117 returns it and the lever 119 to the normal position, the flexible packing of the piston 126 being such as to permit its unretarded upward movement.

In the modification of Fig. 5, the circuit for normally maintaining the magnet 53 of the electromagnet valve E. P. V. energized may be traced as follows: commencing at ground, conductor 128, contacts 103 and contact disc 102, conductors 129 and 130, battery 131, conductor 132, magnet 53, conductor 133, contacts 36—37, conductor 134, contacts 122—123, conductors 135 and 136, front contact 71 of the relay Q, and conductor 137 back to ground. It will be noted that this circuit includes in series the contacts 36—37 and the contacts 122—123, so that if either the engineer's hold-off lever 18 or the fireman's reset plunger 111 is held in its operated position too long, the magnet 53 is de-energized. When the engineer's hold-off lever 18 is moved to the operated position, partly shown in dotted lines, the closing of contacts 23 establish a shunt for the front contact 71 of the relay Q, comprising conductors 138, 139 and said contacts 23, thereby maintaining the magnet 53 energized independently of the dropping of the relay Q. The contacts 103—102 controlled by the stem 54 of the magnet 53 are shunted when the plunger 111 is moved down to close contacts 115—116, this shunt comprising conductors 140, 141 and said contacts 115—116.

The operation of the modified construction of my system shown in Fig. 5 is very similar to that already described, and only the different features need be particularly pointed out. If the engineer fails to operate his hold-off device H at a caution signal, the dropping of relay Q deenergizes magnet 53, thus closing valve 105 and opening valve 104 to supply pressure to the cylinder 44. When the magnet 53 is deenergized, the contacts 102—103 open, so that said magnet will not be reenergized when the front contact 71 of the relay Q recloses. Also, the engineer is not able to reenergize the magnet 53 by operating his hold-off lever 18 to close contacts 23. The magnet 53 can only be reenergized by operation of the plunger 111 to close the contacts 115—116. The plunger 111 is in practice located at such a place that it cannot be reached by the engineer while he retains hold of his brake valve handle, and the engineer there-

fore must call upon the fireman, or some one else, to operate this reset plunger 111. When the contacts 115—116 are closed, the magnet 53 is reenergized, the valve 104 closed to cut off further supply of pressure from the main reservoir, and the valve 105 is opened to exhaust the pressure already in the cylinder 44. It will be observed that this modified arrangement provides an additional element of publicity to the failure of the engineer to operate his holdout device since his neglect is brought to the attention of the fireman. It is contemplated that this, together with the annoyance to the fireman, will induce the engineer to be careful in observing the signals.

Fig. 6 illustrates a modified construction which may be employed for the fireman's reset device. In this modification, instead of the plunger 111 for actuating the lever 119 and the contact spring 115, as in Fig. 5, a threaded shaft 142, with a crank 143 for turning it, carries a nut 144, which is arranged to engage the lever 119 and the contact spring 115 in its opposite extreme positions. As the shaft 142 is rotated the nut travels along said shaft, being held against rotation in a suitable manner, as by a rod 145. When the fireman desires to close the contacts 115—116, he turns the crank 145 in one direction to cause the nut 144 to travel along the shaft until it engages contact spring 115, the lever 119 being released at the same time. By turning the crank 143 in the opposite direction, the nut 144 may be moved back to its normal position so as to restore lever 119 and prevent opening of contacts 122—123. This arrangement makes it more difficult for the fireman to close the contacts 115—116, and then restore the parts to the normal position, thereby adding to his trouble and annoyance. Obviously, the exhaust port 125 must be small enough to give the fireman enough time to move the nut 144 down and back.

In Fig. 7, I have illustrated the trackway apparatus used when the indication of the fixed signals is relied upon to inform the engineer of the entrance of his train into a caution block, and no provision is made for automatic control at the caution signal or corresponding control point. It will be observed that this modification of the trackway equipment consists merely in omitting the trackway element T, at the signal or corresponding control point, together with its controlling line relay 6. On the car, only the relay Q and the time-controlled apparatus K are employed, the E. P. V., the device F for operating the engineer's brake valve, the hold-off device H, and their associated parts and circuits, being omitted. In this arrangement, if the engineer fails to observe the caution indication of a signal, or fails to reduce the speed of his train in obedience

to such signal to a prescribed safe speed before passing the pair of trackway elements T^a-T^b , an automatic brake application, preferably an emergency application, 5 occurs in the same way as previously described. In this connection, I have shown in Fig. 7 the same braking curves as in Fig. 1; but, as previously explained, these braking curves and the speed limits are susceptible of modification and adaptation to fit 10 the varying conditions occurring in practice. I prefer to use a marker, as M , to indicate the location of the trackway elements T^a-T^b , but this is optional.

15 Fig. 8 illustrates how two or more pairs of speed limiting trackway elements T^a-T^b may be employed in the same block, so as to enforce two or more different speed restrictions upon the train during its progress 20 through such block. These pairs of trackway elements T^a-T^b may be located at any desired points in the block, and spaced apart an appropriate distance, so as to cooperate with the time-controlled device K on the 25 car and enforce any desired speed limits, the location and the braking curves shown in Fig. 8 being merely illustrative. This arrangement may be used with or without automatic control at the signal, or corresponding 30 control point. The location of the several pairs of trackway elements T^a-T^b is preferably indicated by markers as M .

Fig. 9 illustrates how a pair of trackway elements T^a-T^b may be used to compel a 35 reduction in speed upon the approach to a switch, or crossover 147. In this arrangement a pair of trackway elements, or a plurality of pairs, if desired, spaced the suitable distance apart, are located at the 40 appropriate point or points in the rear of the switch or crossover, so as to enforce the desired speed restrictions in accordance with the principles hereinbefore explained; and the controlling circuit for the relay 45 or relays governing the coils of these trackway elements is taken through a switch box, as 150, or a circuit controller on the signal governing traffic over this switch or crossover, through a like control device, in accordance with well known signaling practice, so that the coils of these trackway 50 elements are open-circuited when the switch or crossover is set up for a low speed route.

Fig. 10 illustrates how a pair or pairs 55 of trackway elements 151 may be employed to compel a reduction in speed on the approach to a sharp curve 152. In this case the speed limit being always enforced, the trackway elements 151 are merely the magnetic members without coils. The way in 60 which the same principle of control may be applied to any permanent hazard, such as drawbridges, yard limits and the like, will be evident, and need not be shown or 65 described in detail.

I have shown and described different embodiments of my invention, and explained the principles thereof and the manner in which I prefer to practice the invention; but it is evident that various adaptations 70 and modifications, other than those illustrated and described, may be made in my improved system by one skilled in the art without departing from the scope of the invention or deviating from its essential 75 functions and operation. For example, my system is applicable to electric roads as well as steam roads, and may be used in connection with any of the existing block signal systems, with either direct current or alternating current track circuit, all without any changes other than the substitution and selection of well known relays and other devices so as to correspond with the form 80 of energy and the type of signal system. 85

It should be understood that while I have illustrated my invention applied to a system of three-position signaling, the same principles and practice may be employed in connection with two-position home and distant signals. Where three-position signaling is used, and some of the blocks are longer than that required to make a service stop, as is often the case, the trackway element T^1 in these blocks, assuming it is desired to have it convey a true caution indication, would be located some distance in advance of the signal and provided with a marker, as shown in block C, Fig. 1; whereas, with two-position home and distant signals, the trackway element T^1 could be located at the distant signal. These and other adaptations of my system to the differences in the practice of block signaling 100 on railroads, including the application of 101 my system to manually controlled block systems, will be readily apparent, and need not be specifically shown and described.

Although I have particularly described the construction of one physical embodiment of my invention, and explained the operation and principle thereof, nevertheless, I desire to have it understood that the form selected is merely illustrative, but does not exhaust the possible physical embodiments of the idea of means underlying my invention. 110

What I claim as new and desire to secure by Letters Patent of the United States, is:

1. A train control system for railroads 120 divided into blocks, including trackway devices and circuits and vehicle-carried equipment, and comprising means for giving a service brake application, subject to prevention by the engineer, near the entrance to each block when the block ahead is occupied, whereby the engineer may run the vehicle unbraked into a caution block if he so elects, and means comprising two trackway devices spaced relatively close to- 125 130

gether, and car-carried means controlled thereby for giving a stronger brake application independently of the engineer at one or more intermediate points in the block 5 dependent upon the speed of the vehicle at that point or points.

2. In an automatic train control system for railroads divided into blocks, car equipment comprising cautionary control devices 10 adapted to give an automatic brake application subject to prevention by the engineer, and an emergency control appliance adapted to give a stronger brake application independently of the engineer when subjected 15 to successive controlling influences at less than a predetermined time interval apart, an impulse receiving device on the car, track elements adapted to cooperate therewith, there being one track element near the entrance to each block and a pair at one or more intermediate points in the block, and trackway circuits for controlling said track 20 elements of each block in accordance with traffic conditions in the next block in advance. 25

3. In an automatic train control system for railroads divided into blocks, a cautionary track element near the entrance to each block, emergency track elements spaced 30 relatively close together in pairs at an intermediate point or points in the block, trackway circuits for regulating the controlling condition of said track elements of each block in accordance with traffic conditions 35 in the block ahead, and automatic train control equipment on a vehicle adapted to be governed by said track elements, said equipment comprising means controlled by the cautionary track elements for giving a service 40 brake application subject to prevention by the engineer, and other means controlled by the emergency track elements for giving a stronger brake application independently of the engineer. 45

4. In an automatic train control system for railroads divided into blocks, train control apparatus on a vehicle adapted to control its movement in two stages, the first stage being independent of the speed of the 50 vehicle and being preventable by the engineer without applying the brakes, the second stage being dependent upon excessive speed and non-preventable by the engineer, and traffic controlled means for governing 55 the operation of said apparatus to produce the different stages of control in succession, the first near the entrance to a block, and the other at an intermediate point or points therein. 60

5. In an automatic train control system for railroads divided into blocks, the combination with a vehicle equipped with an air-brake system, train control means on said vehicle comprising a brake-setting valve acting 65 on the air-brake system to produce an

automatic application of the brakes, a manually operable hold-off device effective for a limited time only when operated and without effecting any operation of the air-brake system during said limited time, control 70 means for causing operation of the brake-setting valve unless the hold-off device is in its effective condition, said control means being adapted to be actuated by track devices in each block which are governed in 75 accordance with traffic conditions in the block ahead, and other automatic means operated when successive actuations of said control means occur in less than a predetermined interval of time for producing a 80 brake application which is not preventable by the engineer.

6. In an automatic train control system for railroads, automatic train control apparatus on a vehicle including a cautionary 85 control device adapted to give a service brake application, an emergency control appliance adapted to give an emergency brake application, a manually operable holdoff device effective for a limited time without 90 tending to apply the brakes to prevent operation of the cautionary control device but not the emergency control appliance, and means partly on the vehicle and partly along 95 the track for causing operation of said cautionary control device at a control point independent of the speed of the vehicle, and said emergency control appliance at a successive point. 100

7. Automatic train control apparatus for railway vehicles comprising, normally inactive brake control apparatus controlled from the trackway and adapted when operated to tend to produce an automatic application of the brakes which the engineer cannot easily prevent, and a manually operable hold-off device, easily operable by the engineer but effective only if operated prior to the initiation of the operation of said apparatus for preventing such operation in 105 spite of its control from the trackway for a limited time only. 110

8. In an automatic train control system, the combination with a car equipped with an air-brake system, car-carried train control apparatus comprising control means adapted to be automatically actuated from the trackway at control points along the track in accordance with traffic conditions ahead, a brake setting appliance governed by said control means and acting to vent the brake pipe of the air-brake system and cause an automatic brake application, a manually operable hold-off device for preventing 115 operation of the brake setting appliance 120 by said control means, said hold-off device being effective only if actuated prior to the operation of said appliance and if held in its hold-off position longer than a predetermined interval of time acting automatically 125 130

to initiate operation of said brake setting appliance.

9. In an automatic train control system, the combination with car-carried brake control apparatus cooperating with the air-brakes of the car to produce an automatic brake application, of means for automatically initiating the operation of said apparatus from the trackway under unfavorable traffic conditions; a hold-off device conveniently accessible for operation by the engineer and effective only if operated prior to the initiation of operation of said apparatus, for preventing such operation in spite 10 of its control from the trackway, said hold-off device if kept in the hold-off condition longer than a predetermined limited time after each operation thereof acting automatically to actuate said apparatus and cause 15 a brake application, whereby the engineer may prevent an automatic brake application only if he anticipates the operation of the brake control apparatus by a manual operation of the hold-off device and restores the 20 hold-off device to normal within a limited time.

10. In an automatic train control system for railroads, the combination with a car equipped with a braking system and car-carried train control apparatus governing said braking system, of a manually operable hold-off device effective only if put in its hold-off condition prior to initiation of 25 operation of said apparatus to prevent operation of said apparatus, and time-controlled means initiated and restored automatically by the hold-off device as it is changed to its hold-off condition and normal condition respectively, said time controlled means after 30 lapse of a limited interval of time acting to cause an independent operation of said apparatus.

11. In an automatic train control system for railroads, car-carried train control apparatus and a normally closed governing circuit therefor, a control relay having contacts included in said circuit, means on the car and on the track cooperating to cause de-energization of said relay under unfavorable traffic conditions at predetermined 35 control points, a shunt for said contacts, a manually operable circuit controller for closing said shunt, and a time element device released and restored by the operation 40 of said circuit controller for opening said circuit after the lapse of a short interval of time, whereby the manually operable circuit controller cannot be kept closed without causing operation of the train control apparatus.

12. In an automatic train control system for railroads, the combination with a brake-setting device provided with a handle for preventing its movement, power operated 45 means for exerting a strong pressure tend-

ing to actuate said device which may be opposed by the engineer with some difficulty, control means adapted to be governed from the track for controlling said power-operated means, and a separate holdoff device adapted to be easily operated by the engineer and effective only if actuated prior to the initiation of operation of said power operated means for preventing subsequent operation thereof in response to said control means, 50 said hold-off device if held in its active position longer than a limited time acting automatically to initiate operation of said power operated means.

13. In an automatic train control system 55 for railroads, the combination with an engineer's brake valve; of power operated means for exerting a strong pressure tending to operate said brake valve to a brake applying position and for continuing such pressure until restored; manually operable means out of the control of the engineer while at his post for restoring said power operated means; and automatic means partly on the vehicle and partly along the track, 60 having its effective action subject to prevention by the engineer, for causing operation of said power operated means.

14. In an automatic train control system 65 for regulating the movement of trains over tracks divided into blocks, means partly on the train and partly on the track tending to automatically apply the brakes near the entrance to each block and again near the exit end thereof if the next block in advance 70 is then occupied, acknowledging means on the train conveniently operable by the engineer and permitting him to prevent such brake application and proceed with his train unbraked only provided he operates said acknowledging means within a limited time 75 prior to such tendency to apply the brakes and provided he thereafter restores the acknowledging means to normal within a limited time, and means for causing an automatic brake application, dependent upon the speed of the train and which the engineer can not prevent, during the progress of the train through each block with the next block 80 in advance then occupied.

15. In a system for automatically controlling train movement on railroads having tracks divided into blocks, the combination with brake control apparatus on a train, of influence communicating means partly on the train and partly on the track automatically tending to actuate said apparatus at predetermined control points adjacent the entrance and also exit ends of each block if the next block in advance is then occupied, 85 a hold-off device on the train manually operable by the engineer and effective for a limited time only for each operation to prevent such actuation of said apparatus, and other means on the train governed by said 90

- influence communicating means for automatically applying the brakes independently of said hold-off device if the train exceeds the predetermined speed limit during its progress through a block with the next block in advance then occupied.
16. In an automatic train control system for railroads having tracks divided into blocks, a brake setting appliance on the train 10 operating with the air-brake system thereof to produce an automatic service application of the brakes, influence transmitting means on the track cooperating with receiving means on the train inductively through an intervening air-gap and tending to initiate operation of said appliance at a predetermined control point in each block if the next block in advance is then occupied, acknowledging means on the train, manually operable by the engineer and effective for each operation only while the train is traveling a limited distance less than a block length, for preventing operation of said appliance notwithstanding the action of said influence transmitting means, said acknowledging means being incapable of restoring said appliance to permit release of the brakes after operation thereof, means for restoring said appliance, and other means on the train 20 governed by said influence transmitting means for producing an automatic brake application independent of said acknowledging means if the speed of the train is excessive.
17. In a train control system, a brake control device on a vehicle, traffic controlled means for governing said device, and manually operable means effective only when said device is in its normal inactive condition for maintaining it inactive for a limited time only independently of its control by said traffic controlled means.
18. In a train control system, brake control apparatus on a vehicle, traffic controlled means partly on the vehicle and partly on the track for governing said apparatus in accordance with traffic conditions, and manually operable means having a limited time of effective operation for maintaining the apparatus inactive independently of its control by said traffic controlled means, said manually operable means being effective only when the apparatus is in its normal inactive condition.
19. In a train control system, a normally energized brake control device on a vehicle, means for controlling said device from the trackway in accordance with traffic conditions, a circuit controller opened when said device is operated, a normally open auxiliary energizing circuit for said device including said circuit controller, and manually operable means for closing the auxiliary energizing circuit at another point for a limited time only.
20. In a train control system, a brake control device on a vehicle, an energizing circuit therefor governed from the trackway in accordance with traffic conditions, an auxiliary circuit for energizing said device, 70 circuit controlling means for breaking the auxiliary circuit at one point when said device is operated, manually operable means for closing the auxiliary circuit at another point, and means associated with the manually operable means for breaking the main energizing circuit for said device after an interval of time following the operation of said manually operable means.
21. In a train control system, a brake control device on a vehicle governed from the trackway in accordance with traffic conditions, said device when set into operation continuing in operation until restored, manually operable means adapted when operated 80 to prevent operation of the brake control device provided said means is shifted prior to the control of the device from the trackway, and other manually operable means having a limited time of effective action for 85 restoring said device to normal.
22. In a train control system, automatic train control apparatus on a vehicle conditioned from the trackway and adapted to have its operation prevented by the engineer, said apparatus acting unless its operation is thus prevented to cause an automatic brake application, said apparatus also continuing in operation until restored, and means having a limited time of 90 effective action for restoring said apparatus.
23. In a train control system, brake control means on a vehicle governed from the trackway in accordance with traffic conditions and adapted when set into operation 95 to continue in operation until restored, and means having a limited time of effective operation for maintaining said brake control means inactive independently of its control from the trackway, and other manually operable means inaccessible to the engineer while at his post for restoring said brake control means after operation thereof.
24. In a train control system, a normally energized brake control device on a vehicle 115 governed from the trackway in accordance with traffic conditions, said device when set into operation continuing in operation until restored, a restoring circuit for said device, and manually operable means for closing 120 said circuit, said means when maintained in its operated condition longer than a predetermined interval of time acting automatically to break said circuit.
25. In a train control system, train control means on a vehicle having a normally closed operating circuit and an auxiliary retaining circuit, and manually operable means for closing the retaining circuit, said 125 manually operable means when operated 130

opening the operating circuit after an interval of time.

26. In an automatic train control system, automatic apparatus on a vehicle adapted to be controlled from the trackway for causing a brake application, manually controlled means for preventing such brake application if actuated prior to the control of said apparatus from the trackway, and a device for restoring said apparatus to normal, said device automatically causing a brake application if maintained in its restoring condition.

27. Railway traffic controlling apparatus comprising normally inactive means carried on a vehicle for applying the brakes, trackway devices for co-operation with said means to cause an application of the brakes, and manually operable means on said vehicle effective for a given interval of time to prevent a brake application due to co-operation of said first mentioned means with a trackway device.

28. Railway traffic controlling apparatus comprising brake application means on a vehicle, devices located at intervals in the trackway and arranged to co-operate with said means to cause a brake application in the event of dangerous traffic conditions, and manually operable means on the vehicle effective for a given interval of time to prevent a brake application due to such co-operation.

29. Railway traffic controlling apparatus comprising a circuit on a vehicle including a normally closed contact, devices located at intervals in the trackway for opening said contact, manually operable means on the vehicle for closing a branch around said contact and effective for a given interval of time to prevent the de-energization of said circuit by a trackway device, and means controlled by said circuit for causing a brake application when the circuit is open.

30. Railway traffic controlling apparatus comprising an electro-responsive device on a vehicle, a vehicle carried circuit for said device including a source of current and a normally closed contact, devices located at intervals in the trackway for opening said contact, manually operable means on the vehicle for closing a branch around said contact and effective for a given interval of time to prevent de-energization of said electro-responsive device by a trackway device, and means controlled by said electric responsive device when de-energized for causing a brake application.

31. Railway traffic controlling apparatus comprising normally inactive means carried on a vehicle for applying the brakes, trackway devices located at intervals and controlled by traffic conditions in advance for co-operation with said means to cause an application of the brakes, and manually

operable means on said vehicle effective for a given interval of time to prevent a brake application due to co-operation of said first-mentioned means with a trackway device.

32. Railway traffic controlling apparatus comprising devices located at intervals in the trackway and each controlled as to condition by traffic conditions in advance, apparatus on a vehicle co-acting with said devices and arranged to apply the brakes upon encountering a device which is in unsafe condition but not a device in safe condition, and manually operable means on the vehicle effective for a given interval of time to prevent a brake application due to co-operation of said apparatus with a trackway device in unsafe condition.

33. Railway traffic controlling apparatus comprising normally inactive mechanism on a vehicle for applying the brakes, trackway devices for co-operation with said mechanism to cause an application of the brakes, a manually operable member on the vehicle, and normally ineffective means on the vehicle placed in effective condition for a fixed time interval upon operation of said member, said means when in effective condition operating to prevent an application of the brakes due to co-operation of a trackway device with said mechanism.

34. Railway traffic controlling apparatus comprising normally inactive automatic brake application mechanism on a vehicle, means controlled from the trackway for setting said mechanism into operation under unsafe traffic conditions, and manually controllable means on the vehicle effective for a limited interval of time to prevent said mechanism being set into operation from the trackway.

35. Railway traffic controlling apparatus comprising a magnet on a vehicle, apparatus located in the trackway for causing said magnet to be energized while traffic conditions in advance are safe but not when traffic conditions in advance are dangerous, brake application mechanism on said vehicle, means on the vehicle actuated by the de-energization of said magnet for setting said brake application mechanism into operation, and manually operable means on the vehicle effective for a limited time interval for preventing said mechanism from being set into operation.

36. In an automatic train control system for railroads, the combination with a normally inactive brake applying means on a vehicle adapted if operated to cause an automatic application of the brakes of the vehicle, said brake applying means if once operated continuing in operation until restored, means for restoring the brake applying means to normal after operation thereof, a normally energized electro-pneumatic valve acting if

deenergized to operate said brake applying means, governing means for said valve partly on the vehicle and partly on the track for causing deenergization of the valve under 5 dangerous traffic conditions but not under safe traffic conditions, a circuit for maintaining said valve energized independently of its control by said governing means, and manually operable means readily accessible to the 10 operator of the vehicle and acting in its active condition to close said circuit, said manually operable means acting automatically to break said circuit after the lapse of a predetermined interval of time when kept in 15 its active condition.

37. In an automatic train control system, the combination with automatic brake applying apparatus on a vehicle adapted if once operated to continue in operation until 20 restored, means for immediately initiating the actuation of said apparatus from the trackway under dangerous traffic conditions only, manually operable means readily accessible to the operator of the vehicle for 25 preventing such actuation of said apparatus notwithstanding its control from the trackway, said manually operable means being effective to prevent actuation of said apparatus for only a limited time after each 30 manual operation and only if such operation occurs prior to the actuation of said apparatus, and a separate manually operable device for restoring said apparatus to normal.

38. An automatic train control system for railroads comprising, an automatic brake-setting appliance on a vehicle including a normally energized electro-pneumatic valve, traffic controlled trackway means and car-carried means cooperating therewith for causing immediate deenergization of said electro-pneumatic valve under dangerous traffic conditions unless said valve is otherwise maintained energized, a normally open 45 circuit adapted if closed to maintain said electro-pneumatic valve energized regardless of its control by said trackway and car-carried means, means operable manually by the operator of the vehicle to close 50 said circuit for only a limited time after each operation, said brake-setting appliance if once operated by the deenergization of the electro-pneumatic valve continuing in operation until restored irrespective of said manually operable means, and a separate manually operable device for restoring the brake-setting appliance to normal.

39. In an automatic train control system for railroads, the combination with an automatic brake-setting appliance on a vehicle including a normally energized electro-pneumatic valve; traffic controlled means partly on the vehicle and partly on the track for causing deenergization of said electro-pneumatic valve under dangerous traffic con-

ditions but not under safe traffic conditions; and means operable manually by the operator of the vehicle and effective only for a limited time after each operation for maintaining said electro-pneumatic valve energized independently of its control from the trackway by said traffic controlled means; said manually operable means including biased circuit controlling means actuated by pressure in opposition to its bias, and a 70 reservoir used for supplying fluid pressure to said circuit controlling means, the pressure in said reservoir varying through an orifice of restricted area in accordance with the lapse of time after said manually operable means has been placed in its active 75 condition.

40. In a train control system for railroads, the combination with a vehicle equipped with an automatic air brake system of the usual type; brake applying mechanism operable by fluid pressure to act upon the air brake system and cause an automatic application of the brakes; a normally energized electro-pneumatic valve governing the 85 operation of said mechanism; means for governing said electro-pneumatic valve from the trackway in accordance with traffic conditions; and manually operable means on the vehicle readily accessible to the operator 90 of the vehicle for maintaining said electro-pneumatic valve energized independently of its control from the trackway for only a limited time after each manual operation; said manually operable means including a 95 cylinder, a piston therein, a spring tending to move the piston in one direction, circuit controlling means actuated by said piston when shifted in the other direction in opposition to said spring by fluid pressure in 100 said cylinder, a reservoir, a source of fluid pressure, and a manually actuated valve for supplying pressure from said source to the reservoir.

41. In a permissive automatic train control system, the combination with car-carried brake control apparatus including a normally closed valve acting when opened to cause an automatic brake application, impulse transmitting means partly on the vehicle and partly on the track cooperating through an intervening air-gap and automatically tending to open said valve under unfavorable traffic conditions at predetermined control points, and an acknowledging device on the car conveniently operable by the engineer for maintaining said valve closed independently of the control of said impulse transmitting means, said acknowledging device including means responsive to the lapse of time, which means is set into operation each time said device is manually operated and which renders said device ineffective if kept in its operated position 115 longer than a predetermined time, said 120

- acknowledging device being incapable of re-closing said valve after it has once opened, whereby the engineer may forestall an automatic brake application if he operates the 5 acknowledging device at each control point prior to the opening of said valve.
42. A hold-off device for automatic train control systems comprising normally open contacts and normally closed contacts, manually operable means for closing the open contacts, time controlled means set into operation each time said manually operable means is actuated to close the open contacts for opening the closed contacts after a pre-determined time, and a normally open circuit including the open and closed contacts in series.
43. Car equipment for automatic train control systems comprising a normally inactive brake control apparatus, an electro-responsive device governing said apparatus, a manually operable hold-off device which if operated prevents operation of said apparatus, and time controlled means set into operation when the hold-off device is operated for actuating the electro-responsive device after a lapse of an interval of time.
44. In a train control system, the combination with a safety device on a vehicle 30 adapted to be automatically actuated from the trackway at each caution signal and adapted when thus actuated to remain active until restored, a normally open circuit which when closed will maintain said safety device inactive, means for breaking said circuit at one point upon operation of said device, manually operable means for closing said circuit at another point, and other manually operable means for restoring said device after actuation thereof.
45. In a train control system, means partly on the vehicle and partly on the track for producing a control influence on the vehicle at each caution signal, a device governed by 45 said control influence and continuing in operation until restored, manually operable means effective only if actuated prior to the operation of said device for preventing its operation, and other manually operable means for restoring said device after operation thereof, said other manually operable means if maintained in the restoring condition causing an automatic brake application.
46. In an automatic train control system, the combination with automatic brake applying apparatus on a vehicle cooperating with the air-brake system thereof to cause an 50 automatic brake application, trackway means controlled in accordance with traffic conditions ahead, impulse receiving means on the vehicle governed by said trackway means and tending temporarily to initiate the operation of said apparatus when unfavorable traffic conditions exist ahead, manually oper- 55 able means conveniently accessible to the engineer for preventing operation of said apparatus independently of its control by the trackway means, said manually operable means being effective for a limited time 70 only after each operation thereof and only if actuated prior to the initiation of operation of said apparatus, said apparatus when once operated continuing in operation in spite of said manually operable means until 75 restored, and other manually operable means not accessible to the engineer while at his post for restoring said apparatus after operation thereof, said other manually operable means preventing movement of the 80 vehicle if kept in its restoring condition.
47. In an automatic train control system, the combination with brake control apparatus on a vehicle including a normally closed valve and cooperating with the air-brake system of the vehicle to cause an 85 automatic brake application, governing means on the vehicle temporarily actuated at predetermined points along the track if dangerous traffic conditions exist ahead for 90 automatically initiating operation of said apparatus to open said valve, manually operable means conveniently accessible to the engineer for maintaining said apparatus inactive regardless of its control by said governing means, said manually operable means acting automatically to cause a brake application if kept in its active preventing condition for more than a limited interval of time after 95 each manual operation, said governing 100 means if once actuated remaining in that condition beyond the control of said manually operable means until otherwise restored, and other manually operable means not accessible to the engineer while at his 105 post for restoring said apparatus after operation thereof, said other manually operable means also causing a brake application if kept in its active restoring condition.
48. A train control system comprising, 110 in combination with brake control apparatus on a train and control means therefor cooperating with the air-brake system of the train to produce a brake application, of trackway means for temporarily influencing 115 said control means and tending to cause operation of said apparatus at predetermined points along the track when dangerous traffic conditions exist ahead, manually operable means on the train conveniently 120 accessible to the engineer and effective when operated to maintain said apparatus inactive in spite of its tendency to operate in response to the trackway means, said manually operable means being incapable of restoring 125 said apparatus after it has once operated, said manually operable means if kept in its brake preventing position longer than a limited interval of time causing automatic 130 operation of said apparatus, and separate

manually operable means preventing release of the brakes if kept active for restoring said apparatus after operation thereof.

49. In a train control system, the combination with train-carried apparatus comprising, a brake setting appliance normally energized electrically and cooperating with the air-brake system of the train to produce a brake application whenever de-energized, a normally closed energizing circuit for said appliance capable of maintaining it inactive if in that state but incapable of restoring it to its inactive condition after operation thereof, control means when operated tendency to de-energize said circuit, acknowledging means conveniently operable by the engineer at his post for maintaining said circuit energized independently of the operation of said control means, said acknowledging means being thus effective for a limited time only after each operation thereof, of trackway means for operating said control means at predetermined points along the track if dangerous traffic conditions exist ahead and thereby cause an automatic brake application unless the engineer anticipates such brake application by operation of the acknowledging means, and other manually operable means for restoring said brake setting appliance after operation thereof, said restoring means if kept in its restoring condition independently operating said appliance.

50. In a train control system of the permissive type, brake control apparatus on a train cooperating with the air-brake system and including a normally energized electro-pneumatic valve, a normally closed energizing circuit for said valve including contacts opened upon operation thereof, control means on the train governed from the trackway for temporarily interrupting said circuit at predetermined control points along the track under dangerous traffic conditions, a hold-off device on the train, positioned for convenient operation by the engineer and effective for a limited time only after each operation thereof, to maintain said valve energized irrespective of said control means, and a separate manually operable reset device operable to close a shunt circuit around said contacts of the valve and thereby permit restoration thereof, said reset device if kept in its operated position acting to apply the brakes.

51. A system of automatic train control comprising, control means on the train tending to assume its active condition and normally restrained from responding to such tendency, train-carried and trackway impulse elements cooperating inductively through an intervening air gap for temporarily removing such restraint on said control means and thereby permit operation thereof at predetermined control points along the trackway if dangerous traffic con-

ditions exist, a brake setting appliance on the train governed by said control means and acting when operated to cause a brake application, forestalling means on the train conveniently operable by the engineer and effective for a limited time only after each operation thereof, for maintaining said control means inactive regardless of the influence of said trackway elements, such limited time being longer than the interval of time during which said control means tends to assume its active condition, said forestalling means being incapable of restoring said control means after operation thereof, and other manually operable means inaccessible to the engineer while at his post for restoring said control means.

52. In an automatic train control system, the combination with brake control apparatus on a train, of means partly on the train and partly on the track tending to cause operation of said apparatus for a relatively short distance of travel of the train at predetermined control points along the track when dangerous traffic conditions ahead exist, and acknowledging means conveniently accessible to the engineer for maintaining said apparatus inactive independently of the influence of said means, said acknowledging means including a time element device rendering the acknowledging means ineffective if maintained active for more than a predetermined interval of time following each operation thereof, said time element device comprising a piston actuated by fluid pressure, a spring acting on said piston in opposition to the fluid pressure, and a restricted orifice controlling the flow of fluid pressure to one side of the piston.

53. In a system of train control, brake control apparatus on the train including a normally closed valve biased to open, control means for said valve holding it closed by magnetic attraction, traffic controlled track elements influencing said control means inductively through an intervening air gap to release said valve under dangerous traffic conditions at predetermined control points along the track, a hold-off device on the train, conveniently operable by the engineer and effective for a limited time only and only if said valve is then closed, for maintaining it closed independently of the influence of said track elements, and separate means for causing reclosure of said valve after opening thereof.

54. An inductive permissive train control system comprising, a valve on the train biased to open and cooperating with the air-brake system when opened to produce a brake application; a train-carried impulse element and a controllable trackway element cooperating by change in magnetic flux under dangerous traffic conditions to exert a temporary tendency to open said valve at

- predetermined control points along the track restoring means; said valve after once opened remaining open until again closed by said restoring means; a movable member conveniently operable by the engineer; and means including a device operable in accordance with the lapse of time and governed by the movement of said member for maintaining said valve closed independently of its control by said impulse elements, provided the valve is then closed and provided said member is restored to the normal position after each operation thereof within a limited time.
55. A train control system for railroads equipped with block signals, the combination with track elements located adjacent to the block signals and having their controlling condition automatically governed in accordance with the indications thereof, of train carried apparatus comprising, a normally closed valve acting when opened to cause venting of the brake pipe of the train and thereby produce a brake application, impulse receiving means cooperating with said track elements through an intervening air gap by transfer of magnetic flux and automatically tending to open said valve if the corresponding block signal has an unfavorable indication, forestalling means on the train conveniently operable by the engineer and effective for a limited time only for each operation to keep said valve closed in spite of the influence of an active track element, said forestalling means being incapable of reclosing the valve after it has once opened, and other means for causing restoration of said valve.
56. In an automatic train control system of the permissive type, the combination with a normally energized electro-responsive device on the train acting when de-energized to cause an automatic brake application, closed contacts opened upon de-energization of said device, an energizing circuit for said device including said contacts, impulse receiving means on the train automatically actuated in response to influences from the trackway under dangerous traffic conditions for making a break in said circuit, acknowledging means conveniently operable by the engineer for establishing a shunt circuit around said break and thereby maintaining said device energized in spite of said impulse receiving means, provided it is then energized, said acknowledging means being effective to maintain said device thus energized for a limited time only for each operation, and other means for restoring the electro-responsive device to its energized condition after de-energization thereof.
57. In an automatic train control system of the intermittent inductive type, a normally energized electro-responsive device on the train cooperating when de-energized with the air-brake equipment to produce a brake application, said device having stick contacts opened when it operates, a track element having a magnetic core and a governing circuit and assuming its active condition unless said governing circuit is closed, impulse receiving means on the train including a normally closed circuit controller inductively influenced through an intervening air gap by said track element in its active condition and opening said circuit controller temporarily during movement of the train by the track element, acknowledging means conveniently operable by the engineer and including normally open contacts quickly closed upon operation thereof and normally closed contacts opened after a limited time while the acknowledging means is in its operated condition, a normally closed energizing circuit for said electro-responsive device including in series said stick contacts, circuit controller and normally closed contacts of the acknowledging means, a shunt circuit for said circuit controller closed by the normally open contacts of the acknowledging means, and a reset switch not accessible to the engineer while at his post for closing a shunt circuit around said stick contacts and thereby permit re-energization of the electro-responsive device after operation thereof, said reset switch if kept in its operated position preventing release of the brakes.
58. In an automatic train control system, an electro-responsive device on the train controlling the air-brakes and having stick contacts opened upon operation of the device, a stick circuit for said device including said contacts, automatic means for intermittently and temporarily making a break in said circuit during the movement of the train along the track when dangerous traffic conditions exist ahead, a manually operable contactor on the train for closing a shunt around said break and thereby maintain said device energized independently of the trackway control, said contactor being incapable of restoring said electro-responsive device after it has once operated and if held in its operated position longer than a limited time independently interrupting said stick circuit, and other means on the train operable to restore the electro-responsive device after operation thereof.
59. In a train control system of the permissive type, the combination of automatic brake control apparatus on a train tending to assume its active condition and apply the brakes, a normally closed circuit on the train effective so long as energized to maintain said apparatus inactive but incapable of restoring it after it has once become active, governing means automatically actuated from the trackway for opening said

- 5 circuit at one point temporarily at predetermined control points along the track under dangerous traffic conditions, acknowledging means conveniently operable by the 5 engineer for maintaining the flow of current in said circuit through said apparatus in spite of the influence of said governing means, said acknowledging means if kept in its operated position longer than a limited 10 time each time operated causing an independent operation of said apparatus, said limited time being greater than the time during which the governing means opens said circuit, and reset means on the train 15 for restoring said apparatus to normal.
60. In a train control system for railroads equipped with block signals, the combination with a track element adjacent each signal and having a governing circuit opened if 20 the corresponding signal indicates caution, brake control apparatus on the train, an impulse receiving element on the train influenced inductively through an intervening air gap by said track element if its governing 25 circuit is open for tending to initiate operation of said apparatus, forestalling means on the train, easily operable by the engineer and effective for a limited time only and also only if actuated prior to the 30 passage of the train by an active track element, for maintaining said apparatus inactive in spite of the influence of such active track element, and other means for restoring said apparatus to normal.
35. 61. In a train control system of the permissive type for use in connection with block signals, the combination with influence transmitting means partly on the track and partly on the train and temporarily effective near 40 each signal if it indicates caution, of automatic brake control apparatus on the train including a normally energized electro-pneumatic valve governed by said influence transmitting means and tending to de-energize 45 said valve temporarily, acknowledging means on the train effective for a limited time only for each operation for maintaining said electro-pneumatic valve energized in spite of the controlling effect of said influence communicating means, said acknowledging means being effective only if actuated prior to the transmission of the influence, and a reset device for restoring the electro-pneumatic valve to normal, said reset device 50 if kept in the restoring condition acting to cause deenergization of said valve regardless of the acknowledging means or the fact that the reset device is in the restoring position.
60. 62. A train control system of the permissive type comprising, in combination with a block signal system, brake control apparatus on the train, influence communicating means tending to initiate operation of said apparatus at a predetermined control point adj-

cent each signal when it indicates unfavorable traffic conditions in advance, acknowledging means on the train conveniently operable by the engineer and effective at once to maintain said apparatus inactive provided 70 it is then inactive, said acknowledging means if kept in its effective condition longer than a limited time for each operation nevertheless operating said apparatus to produce an automatic brake application, a reset device, 75 said apparatus after operation thereof remaining in that state until restored by said reset device, whereby the engineer must operate his acknowledging means before 80 passing the control point associated with 85 each unfavorable signal indication and must thereafter return his acknowledging means to normal within a limited time in order to avoid an automatic brake application and the consequent necessity of operating the reset device.

63. Car equipment for train control systems of the permissive type comprising a normally closed valve biased to open and cause a brake application when opened, a 90 source of energy, control means normally supplying energy from said source to said valve to keep it closed, means influenced from the trackway for governing said control means to discontinue temporarily said 95 supply of energy, acknowledging means effective for a limited time only for each operation and only if operated prior to the opening of said valve for supplying energy thereto irrespective of the action of said control 100 means, said valve when once opened remaining open until restored by other means, and remote control means for restoring said valve.

64. In a train control system, the combination with the engineer's brake valve of the usual air-brake system, fluid pressure means for automatically operating said brake valve, a normally energized electro-pneumatic valve governing the fluid pressure means, a 110 normally closed circuit on the train controlling said valve, said valve remaining de-energized upon interruption of said circuit until otherwise restored, means controlled from the trackway for opening said circuit 115 at one point, acknowledging means for maintaining the flow of current in said circuit regardless of such opening thereof, said acknowledging means being effective for a limited time only for each operation, and 120 manually operable means for restoring said valve.

65. In a train control system of the permissive type, the combination with automatic brake applying apparatus including means 125 for moving the engineer's brake valve of the usual air-brake system, means tending to cause operation of said apparatus at predetermined control points along the track under unfavorable traffic conditions, and ac- 130

- knowledging means conveniently operable by the engineer for maintaining said apparatus inactive in spite of its control from the trackway, said acknowledging means effective only if operated prior to the initial operation of said apparatus and likewise producing an automatic brake application after a limited time if kept in its active brake preventing condition.
66. In an automatic train control system, the combination with the air-brake system of a train and the usual engineer's brake valve for controlling it, of brake control apparatus on the train including means for automatically operating the engineer's brake valve, means for controlling said apparatus automatically from the trackway dependent upon traffic conditions in advance, and acknowledging means on the train manually operable to prevent operation of said apparatus and effective only if operated prior to the initial operation of said apparatus, said acknowledging means automatically acting if kept in such preventing condition to initiate independently operation of said apparatus but only after a limited interval of delay.
67. In a train control system for railroads provided with blocks, brake control apparatus on a train including a normally energized electro-responsive device, means tending to de-energize said device and cause operation of said apparatus for a limited distance of travel of the train at a predetermined control point associated with each block if the block next in advance is then occupied, acknowledging means conveniently operable by the engineer to forestall such brake application, said acknowledging means being ineffective after said electro-responsive device having once responded to its de-energization, and means on the train set into operation upon actuation of said acknowledging means to impose an automatic control on the movement of the train independently of the acknowledging means after an interval of delay if the acknowledging means is maintained in its actuated position.
68. A system of automatic train control for railroads equipped with track circuited blocks, comprising, in combination with trackway and train-carried means cooperating inductively through an intervening air gap to produce a control influence on the train at a predetermined control point in each block if the next block in advance is then occupied, brake applying mechanism on the train governed by said means and tending to automatically apply the brakes in response to such control influence regardless of the speed of the train, and manually operable acknowledging means on the train permitting the engineer to prevent operation of said mechanism in spite of said control influence, provided he operates said acknowledging means within a limited time prior to reception of said control influence and also thereafter restores the acknowledging means to normal after each operation.
69. An acknowledging device for permissive train control systems comprising, a piston actuated by fluid pressure, manually controllable means to supply fluid pressure to said piston, a spring acting on the piston in opposition to the fluid pressure, means restricting the rate of flow of fluid pressure to act on the piston, and brake applying means automatically actuated upon movement of the piston to one extreme position.
70. In a system of permissive train control for railroads equipped with blocks, the combination with train-carried apparatus comprising, a brake control appliance, a normally energized electro-responsive device governing said appliance and having stick contacts opened upon operation thereof, a reset switch for closing a shunt circuit for said stick contacts of the electro-responsive device to permit restoration thereof, an acknowledging contactor having normally open and normally closed contacts, said normally closed contacts being automatically opened after an interval of delay while the acknowledging contactor is in its active position, an impulse receiving element including a biased armature and normally closed contacts opened upon retraction of the armature, a shunt circuit for the contacts of said armature established by the closure of the normally open contacts of the acknowledging contactor, a normally closed energizing circuit for said electro-responsive device including in series its stick contacts, the normally closed contacts of the acknowledging contactor, and the contacts of said armature, of the track element associated with each block and having a governing circuit, each track element inductively influencing said impulse receiving element on the train through an intervening air gap unless its governing circuit is closed, and means for opening the governing circuit of the track element of each block if the next block in advance is then occupied.
71. In an automatic train control system, the combination with normally energized brake control apparatus on a vehicle, a normally open auxiliary energizing circuit for said apparatus, of manually controlled means for preventing operation of said apparatus by closing said circuit, said means being automatically rendered ineffective by the opening of said circuit after a limited time following its initial operation.
72. In an automatic train control system for railway vehicles, brake control apparatus on the vehicle having an energizing circuit, traffic controlled means partly on the vehicle and partly on the track for interrupting said energizing circuit, a normally

open auxiliary maintaining circuit including the brake control device, manually operable means for closing said maintaining circuit at one point, and means responsive to 5 the operation of the brake control device for interrupting the auxiliary circuit at another point when said device is operated.

73. Railway traffic controlling apparatus comprising a stretch of railway track, a 10 railway train, a magnet on the train arranged when deenergized to apply the brakes, means partly on the train and partly in the trackway to successively deenergize, re-energize, and again deenergize said 15 magnet as the train approaches another train ahead, and manually operable means on the train effective for a limited interval of time only after each operation thereof

and only if operated prior to the deenergization of said magnet for maintaining said 20 magnet energized during the interval of deenergization thereof by said first mentioned means.

74. Railway traffic controlling apparatus comprising a stretch of railway track, a 25 railway train, a magnet on the train arranged when deenergized to apply the brakes, manually operable means on the train effective for an interval of time to prevent application of the brakes when said 30 magnet is deenergized, and means partly on the train and partly in the trackway to successively deenergize, re-energize, and again deenergize said magnet as the train approaches another train ahead.

WINTHROP K. HOWE.

open auxiliary maintaining circuit including the brake control device, manually operable means for closing said maintaining circuit at one point, and means responsive to 5 the operation of the brake control device for interrupting the auxiliary circuit at another point when said device is operated.

73. Railway traffic controlling apparatus comprising a stretch of railway track, a 10 railway train, a magnet on the train arranged when deenergized to apply the brakes, means partly on the train and partly in the trackway to successively deenergize, re-energize, and again deenergize said 15 magnet as the train approaches another train ahead, and manually operable means on the train effective for a limited interval of time only after each operation thereof

and only if operated prior to the deenergization of said magnet for maintaining said 20 magnet energized during the interval of deenergization thereof by said first mentioned means.

74. Railway traffic controlling apparatus comprising a stretch of railway track, a 25 railway train, a magnet on the train arranged when deenergized to apply the brakes, manually operable means on the train effective for an interval of time to prevent application of the brakes when said 30 magnet is deenergized, and means partly on the train and partly in the trackway to successively deenergize, re-energize, and again deenergize said magnet as the train approaches another train ahead.

WINTHROP K. HOWE.

DISCLAIMER

1,551,515.—*Winthrop K. Howe, Rochester, N. Y. AUTOMATIC TRAIN-CONTROL SYSTEM.* Patent dated August 25, 1925. Disclaimer filed February 16, 1934, by the assignee, *General Railway Signal Company*.

Hereby disclaims from claim 72 any system of automatic train control, involving the combined automatic and manual control of the air brake system, except where the "manually operable means" is separate and distinct from the engineer's brake valve handle, and may be manipulated to forestall an automatic application of the brakes, without manually applying the brakes.
